ABSTRACT: Cable assemblies are to be bound by means of a strap whose ends are held by a lock member. The improved appliance comprises an elongated body with a holder for a lock member to be fixed and a magazine for lock members extending parallel to the body. The magazine is pivoted so that the magazine mouth can be moved towards the holder to push lock members through a guide duct joining the magazine mouth and the holder. When the magazine is subsequently moved away from the holder the mouth is opposite an empty part of the guide duct and another lock member from the magazine is urged into the empty space. To load the magazine, the lock members are attached to a flexible belt and are fed into guides. One guide leads the lock members into the magazine and the guide leads the belt first parallel to the lock member guide then sharply away from this to separate the belt from the lock members.

TOOL FOR BINDING CABLE HARNESSES

This invention relates to an appliance for binding cable assemblies or the like by means of a strap, whose ends are fastened by a lock member, which appliance comprises a longitudinally extended tool body, which has at the front end a holding member for the lock member to be processed, a magazine fitted parallel to the tool body for a plurality of lock members, and devices for transferring the particular lock member located at the mouth of the magazine into the holding member.

In known tools of this kind the magazine is pivotably fixed to the tool body in such a way that the mouth of the magazine can be swiveled in front of the holding member for the lock member to be processed, the lock member located in the magazine mouth being released by a mechanism actuated by the pivoting movement and pushed by spring force into the holding member of the tool. This magazine arrangement and operation is comparatively complicated.

One object of the invention is to provide an appliance for binding cable assemblies of the kind mentioned above, but which is provided with a magazine which is more simply constructed and simpler to operate.

This object is attained in accordance with the invention in that the mouth of the magazine, which is arranged next to the holding member for the lock member to be processed, is connected with the said holding member by a guide duct, through which the particular lock member located at any instant in the magazine mouth, can be pushed into the holding member by means of a thrust device.

The magazine therefore maintains continuously its position substantially parallel to the tool body. The device for thrusting the lock member located in the mouth of the magazine to the holding member, is only required from time to time.

In a particularly advantageous embodiment of the invention the magazine can be swiveled in such a way that the magazine mouth can be brought nearer the holding member by at least the width of one lock member, and the guide duct exerts a greater frictional force on the foremost lock member of the magazine located therein than on the second foremost lock member located behind this in the magazine. Here the magazine itself is the thrust device.

The filling of the magazine is also a problem in the case of known appliances, since the lock members have to be filled individually into the magazine, care having to be taken regarding the correct positioning of each lock member in the magazine. The invention is further directed to the task of forming the magazine in such a way that it can be filled in a considerably simpler fashion, and to provide a store unit of lock members which can be fed as a whole into the magazine in a simple manner. However the lock members must not be fixedly connected in the magazine.

The solution provided by the invention to these problems is that the lock members are held by a holding strip, which is provided, at spaced distances equal to the width of one lock member, with protuberances or recesses adapted to the slots, bores or dowel-type projections of the lock members, on which protuberances or in which recesses the lock members are pushed, and that the magazine is provided with guide devices for the lock members and for the holding strips, of which the guide device for the lock members leads into a duct-type magazine chamber accommodating the lock members, while the guide device for the strip extends first of all at a slight distance (corresponding to the cross-sectional construction of the supply strip) from the guide device for the lock members, and is then separated from this at an acute angle.

Specific embodiments of the invention will now be described by way of example with reference to the accompanying drawings in which:

FIGS. 1 to 3 show longitudinal sectional views of a tool, in a plane common to the holding device for the lock member and the lock member magazine, each with the parts in a different stage of operations.

FIGS. 4 to 6 show longitudinal sectional views of a lock member magazine similar to that of FIGS. 1 to 3 but of

modified construction, the section being taken on the side of the magazine farthest from the front plate,

FIG. 7 shows a cross section of a detail of the magazine shown in FIGS. 4 to 6, and

FIGS. 8 and 9 are respectively cross-sectional and elevational views on a larger scale of a belt of lock members.

As diagrammatically indicated in FIGS. 1 to 3 a tool body 301 has a front plate 302 with a cutaway portion 303 as a holding member for a lock member 304 to be locked. The closure and cutting devices are merely indicated at 305. Parallel to the tool body 301 lies a magazine 306 holding a plurality of lock members, which are impelled by a spring device 307 in the direction of the arrow. In the front part of the tool is located a transverse duct, partly visible at 308 in FIG. 3, leading from the magazine mouth to the holding member 303. This duct is made comparatively narrow, so that it holds the lock members located therein, by friction. A wall part 309 of the magazine projects into the duct. The magazine is pivotable as can be seen by reference to FIGS. 1 and 3, about an axis perpendicular to the plane of representation.

The apparatus operates as follows:

When the lock member 304 located in the holding member 303 is locked and removed, the holding member 303 is free (FIG. 2). The magazine 306 is then pressed by hand in the direction of the arrow 310 (FIG. 3) towards the holding member 303, by which the lock member 311 located in the duct 308 is pushed into the holding member 303. The lock member 312 now assumes the position formerly held by the lock member 311. After the return of the magazine from the position in FIG. 3 under the action of a spring (not shown) into the position shown in FIG. 1, the lock member 313 is pushed by the spring device 307 forward into the duct to the position assumed in FIG. 1 by the lock member 312. This sequence of events is repeated each time a lock member is removed from the holding member 303.

In order to facilitate the loading of the magazine with lock members it is preferred to use the embodiment shown in FIGS. 4 to 6. In this embodiment, the magazine forms a duct 501 of substantially rectangular cross section which is open in the manner of a slot, at the bottom at 502. A spring device 503 impels a lock member 504 located in the duct in the direction of the arrow 517 (FIG. 6). A ram 505 of the spring device has finger 506 projecting through the slot 502. Components 507 form an insertion device for a row of lock members, which appears partly in side view in FIG. 9, while FIG. 8 shows a cross section. It consists of a belt 508, which has on a base 509 dowel-type projections 510 spaced apart by a distance equal to the width of one lock member 504. On these dowels the lock members are applied in continuous rows and are held by the friction of the dowels 510 in the bores of the lock members. The insertion device 507 has a guide duct 511 for the row of lock members and a narrower guide duct 512 for the belt 508, which are separated by a projection 513, as can best be seen from the cross section shown in FIG. 7. The guide duct 511 opens into the magazine duct 501, while the guide duct 512 for the belt or strip extends first of all adjacent and parallel to the guide duct 511 and then separates from it at an acute angle at 514, to leave the tool body again at 515.

The mode of operation of the apparatus is as follows:

When with the aid of finger 506 the ram 505 is moved to and held in the retracted position shown in FIGS. 4 and 5 and a lock member strip or belt is fed in the direction of the arrow 516 into the insertion device, the lock members travel through the duct 511 as indicated in FIG. 5 into the duct 501 (FIG. 6), while the belt 508, guided through the ducts 512, 514, 515, is pushed further out, by which the lock members are separated from the belt.

The apparatus offers the advantage that the lock members are available in a large unit corresponding to the dimensions of the magazine, which unit can be inserted in a simple manner into the magazine, and that the lock members nevertheless are not reciprocally fixed in the magazine, but can be removed one by one from the said magazine without any resistance.

I claim:

1. In an appliance for binding cable assemblies or the like by means of a strap whose ends are held by a lock member having a bore, said appliance comprising:
  - a. a magazine for holding said lock members; and
  - b. a storage belt of lock members for filling said magazine; the improvement that
  - c. said lock members are held by a holding belt;
  - d. said holding belt is provided with protuberances adapted in shape to said bores of the lock members;
    1. said protuberances being at spaced distances equal to the width of one said lock member; and
    2. said lock members being placed on said protuberances;
  - e. first guide means for the lock members;
  - f. second guide means for the holding belt;
  - g. a ductlike magazine chamber in said chamber,
  - h. said first guide means leading into said ductlike magazine chamber and said second guide means extending first at a slight distance, corresponding to the cross-sectional shape of said holding belt, from the first guide means and then separating from said first guide means at an acute angle.
2. In an appliance for binding cable assemblies or the like by means of a strap whose ends are held by a lock member having a dowel-type projection said, appliance comprising:
  - a. a magazine for holding said lock members; and
  - b. a storage belt of lock members for filling said magazine; the improvement that;
  - c. said lock members are held by a holding belt,
  - d. said holding belt is provided with recesses adapted in shape to said projections of the lock members;
    1. said recesses being at spaced distances equal to the width of one said lock member, and
    2. said lock members being placed in said recesses;
  - e. first guide means for the lock members,
  - f. second guide means for the holding belt,
  - g. a ductlike magazine chamber in said chamber,
  - h. said first guide means leading into said ductlike magazine chamber and said second guide means extending first at a

- slight distance, corresponding to the cross-sectional shape of said holding belt, from the first guide means and then separating from said first guide means at an acute angle.
5. 3. In an appliance for binding cable assemblies or the like by means of straps whose ends are secured by lock members, an elongated tool body having a front end; holding means for said lock members, said holding means being arranged at said front end of the elongated tool body; a pivotally mounted magazine adapted to contain a plurality of said lock members and having an outlet mouth therefor; said magazine being normally disposed substantially parallel to said elongated tool body but being tiltable so as to bring said mouth nearer to said holding means by at least the width of one of said lock members;
  - 10 15 10. guide duct connecting said magazine mouth with said holding means adapted to receive said lock members slideably therein for transferring the latter from said magazine to said holding means, said guide duct being constructed so as to subject the foremost lock member located therein to a frictional force greater than that exerted on the second foremost lock member; and thrust means for pushing said lock members from said magazine through said mouth thereof and said guide duct towards said holding means.
  - 15 4. In an appliance for binding cable assemblies or the like by means of straps whose ends are secured by lock members, an elongated tool body having a front end; holding means for said lock members, said holding means being arranged at and rigidly connected to said front end of the elongated tool body; a magazine adapted to contain a plurality of said lock members, said magazine being disposed substantially parallel to said elongated tool body and having an outlet mouth for said lock members; guide duct means stationary relative to said tool body and forming a rigid unit therewith, said guide duct means extending from said magazine mouth to said holding
  - 20 30 35 30. means for receiving said lock members slideably therein and transferring the latter from said mouth to said holding means; and thrust means for pushing said lock members from said magazine towards said guide duct means and said holding means.
